CLAIM

The ornamental design for a baler intake cylinder as shown and described.

DESCRIPTION

FIG. 1 is a front view of a baler intake cylinder showing my new design;

FIG. 2 is a rear view of the baler intake cylinder;

FIG. 3 is a right side view of the baler intake cylinder;

FIG. 4 is a left side view of the baler intake cylinder;

FIG. 5 is a top view of the baler intake cylinder;

FIG. 6 is a bottom view of the baler intake cylinder;

FIG. 7 is a top front side perspective view of the baler intake cylinder; and,

FIG. 8 is a bottom rear side perspective view of the baler intake cylinder.

1 Claim, 6 Drawing Sheets
